APPARATUS FOR MULTIPLE ELECTRIC IMPULSE PRODUCTION

William Arthur Ward, Norwood, Mass., assignor to
United States Scientific Instruments, Inc., Watertown,
Mass., a corporation of Massachusetts

Filed Dec. 17, 1962, Ser. No. 245,216
20 Claims. (Cl. 315—241)

The present invention relates to methods of and apparatus for multiple electric-impulse production and, more specifically, to apparatus for producing successive electrical-impulse discharge, including light flashes for such purposes as stroboscopy or flash photography or the like.

While multiple electrical-impulse discharges have been produced in stroboscopes and similar pulse modulator circuits, there is an inherent restriction upon the ultimate speed of successive discharges residing in the tendency of the load device to "hold over" in conduction. The problem of producing very short and rapidly occurring successive electrical discharges in a single load device, such as a single rapid-recovery flash lamp or similar triggered device, has previously demanded the use of a plurality of separate trigger circuits and associated energy-storage circuits. Not only is this costly and complex, but there is still the possibility of the flash device remaining conductive between intended successive discharges; and often the successive discharges, if produced, will not be of substantially the same intensity.

It is, accordingly, to the solution of the problem of providing a new and improved method of and apparatus for high-speed multiple equal-intensity electrical impulse discharges that shall not be subject to the above limitations, that the present invention is primarily directed. In summary, this end is attained through a pair of critically relatively proportioned energy-storage capacitors charged to different voltages and interconnected by a resonant charging circuit to effect at least a pair of successive discharges through a common load device, at the end of which substantially all voltage is automatically removed from the load device to prevent "hold over" or similar phenomena.

A further object of the invention is to provide a novel impulse-producing circuit of more general utility, also.

An additional object is to provide a novel multiple light-flash producer, where the term "light" is intended to embrace both visible electromagnetic radiations and longer and shorter wave-length radiations, as well.

Other and further objects will be explained hereinafter and will be more particularly pointed out in connection with the appended claims.

The invention will now be described in conjunction with the accompanying drawing the single figure of which is a schematic circuit diagram of a preferred embodiment of the invention.

For purposes of illustration, the invention is described as applied to the problem of producing a pair of successive substantially equal-intensity short light flashes in flash tubes, such as the type described, for example, in United States Letters Patent No. 2,977,508, issued March 28, 1961, to Kenneth J. Germeshausen; though the invention is equally obviously applicable to other kinds of flash tubes and other types of discharge-responsive load devices where the features of the invention are desired. Such a flash-tube load is shown at 1 provided with a pair

2

of principal electrodes 3 and 5' between which an electrical-impulse discharge from capacitor C₁ may occur through the gaseous medium of the tube 1, in response to the triggering or rendering-effective of the tube 1 by a trigger impulse applied to intermediate trigger electrodes 5. The trigger electrodes 5 may receive the trigger impulse through separate isolating capacitive couplings C' from a transformer T that is energized by trigger pulses from a trigger circuit 7, as of the type described in the said Letters Patent, or any other well-known type.

Energy-storage capacitor C₁ (or capacitors) is charged from a voltage source 2, 4 of predetermined voltage value V (such as a D.C. source), through a large charging resistor or impedance R₁. Upon the rendering of the normally ineffective or non-conducting tube 1 effective by application of a trigger pulse P₁ to the trigger electrodes 5, the energy stored or charged in capacitor C₁ will become discharged as an impulse or flash through the tube 1 between the principal electrodes 3 and 5', energizing the tube 1 to produce a flash of light the intensity or energy of which is related to the magnitude of the predetermined voltage V to which the capacitor C₁ had initially become charged (energy = $C_1 V^2 / 2$).

Even were the charging cycle or time constant of capacitor C₁ through R₁ fast enough, it is difficult to extinguish and re-flash the tube 1 immediately following this first flash because of the tendency of the tube to "hold over" in conduction—i.e., a finite recovery time for deionizing the gaseous medium in the tube 1—particularly in the presence of the voltage building up in the recharging of C₁ across electrodes 3 and 5'.

In accordance with the invention, however, at the same time C₁ was initially being charged to voltage V through R₁, a second critically valued capacitor C₂ was being charged from a voltage source 2'-4 of value substantially one-half that of the source V (i.e. V/2) through resistor or impedance R₂. By preadjusting the value of C₂ at the critical value of substantially four times that of C₁ (C₂ = 4C₁), and connecting a series resonant voltage-doubling or boosting circuit comprising inductance L and check valve D between C₂ and C₁, the following phenomenon has been found to occur. After C₁ has discharged its initial charged voltage V, energizing the tube 1 to produce the first flash therethrough, C₂ will deliver its charged voltage V/2 to C₁, but with double voltage (i.e. a total voltage V) because of the series resonant voltage-doubling or boosting action of the circuit C₂-L-C₁. C₁ then receives a fast re-charge to voltage V, the speed of which is determined by the half-period of the oscillation frequency f of the resonant circuit C₂-L-C₁ (i.e.,

$$f = \frac{1}{2} \pi \sqrt{LC_1 C_2 / (C_1 + C_2)}$$

If a second trigger pulse P₂ is applied at T at the end of such half-period, a second energization flash will occur in tube 1 as C₁ again discharges the voltage V transferred to it from C₂ through L and the check valve D. This second flash will be of intensity substantially equal to the intensity of the first flash since the same voltage V has been discharged through the tube 1. The inductance L, moreover, is preferably a saturable reactor that effects a short delay in transfer of charge from C₂ to C₁ and then, upon saturation, causes rapid voltage transfer during the half-period of the oscillation frequency f.

At the end of the second discharge, however, since R_1 is made large, as before explained, so as to provide a relatively slow re-charging cycle of C_1 through R_1 ($C_1R_1 >$ half-period of f), substantially no or little voltage, herein-after referred to as negligible voltage, will be present across C_1 and thus at the tube electrodes 3 and 5', so that no "hold over" is possible. The re-charging time of the capacitors should preferably be about ten percent of the time T_1 required between successive pairs of flashes.

Two very rapid, sharp and equal-intensity flash impulses are thus produced reliably without spurious "hold over" and with a single trigger circuit. Provided the same critical relative voltage and capacitor values and relation between the resonant charging circuit half-period and multiple trigger-pulse repetition rate are maintained, additional capacitors and resonant charging circuits may be added for additional multiple pulses or flashes.

As an example, successive pairs of equal-intensity light flashes of about 2-10 microseconds duration spaced about 350 microseconds apart have been produced with an FX6A type flash tube 1 (Edgerton, Germeshausen & Grier, Inc.) triggered by pulses of about two microseconds duration spaced about 350 microseconds apart, with $C_1 = .33 \mu\text{farad}$, $C_2 = 1.33 \mu\text{farad}$, $V = 500$ volts, saturable $L = 50$ millihenries, having about 150 microseconds delay before saturation, $R_1 = 60$ K ohms, $R_2 = 15$ K ohms, and $f = 1.5$ kilocycles (half-period about 350 microseconds). The repetition rate of the pairs of trigger pulses from trigger circuit 7 for producing successive sets of double flashes produced an interval T_1 between successive pairs of flashes of about 40 milliseconds.

Further modifications will occur to those skilled in the art and all such are considered to fall within the spirit and scope of the invention as defined in the appended claims. Included in such, is the provision of a diode D_1 shunting resistor R_1 to prevent overcharging beyond the value V and clamping the voltage of capacitor C_1 to a predetermined value, particularly in the event that the voltage applied at 2'-4 is somewhat greater than $V/2$.

What is claimed is:

1. An electric-impulse-producing apparatus having, in combination, first energy-storage means of predetermined value, a normally ineffective impulse-producing load connected across the first energy-storage means, means for storing energy in the first energy-storage means with a predetermined voltage, second energy-storage means of value greater than that of the first energy-storage means, means for storing energy in the second energy-storage means with a further voltage less than the said predetermined voltage, a voltage-boosting circuit connecting the first and second energy-storage means together, and means for rendering the impulse-producing load effective at a first instant of time to enable impulse energization of the load by the stored energy in the first energy-storage means and at a second instant of time later to enable a second impulse energization of the load by the first energy-storage means in which energy has been re-stored from the second energy-storage means through the voltage-boosting circuit.

2. Apparatus as claimed in claim 1 and in which the second energy-storage means is substantially four times the value of the first energy-storage means and the further voltage is substantially one-half that of the predetermined voltage.

3. Apparatus as claimed in claim 2 and in which the voltage-boosting circuit is substantially a voltage doubler.

4. Apparatus as claimed in claim 3 and in which the first and second energy-storage means comprise capacitors.

5. Apparatus as claimed in claim 3 and in which the voltage doubler comprises a resonant circuit the half period of which is at least substantially equal to the time interval between the said first and second instants of time.

6. Apparatus as claimed in claim 5 and in which the resonant circuit includes a check valve.

7. Apparatus as claimed in claim 5 and in which the said rendering means comprises a source of trigger impulses.

8. Apparatus as claimed in claim 7 and in which the said load comprises a flash tube having principal and trigger electrode means with the principal electrode means connected across the first energy-storage means and the trigger electrode means connected with the said source of trigger impulses.

9. Apparatus as claimed in claim 5 and in which the charging time of the first energy-storage means is greater than the said half-period.

10. Apparatus as claimed in claim 3 and in which the said load comprises a flash tube having electrodes connected across first energy-storage means.

11. Apparatus for producing successive electrical impulses, that comprises, means for storing at a first location a predetermined voltage to a predetermined capacity, means for substantially simultaneously storing at a second location less than the predetermined voltage but with a greater capacity, means for discharging the stored predetermined voltage at the first location to produce a first electrical impulse, means for transferring the stored voltage at the second location to the first location while substantially boosting the voltage, and means for discharging the transferred boosted voltage at the first location to produce a second electrical impulse.

12. Apparatus for producing successive electrical impulses, that comprises, means for storing at a first location a predetermined voltage to a predetermined capacity, means for substantially simultaneously storing at a second location substantially half the said predetermined voltage with substantially four times the said capacity, means for discharging the stored predetermined voltage at the first location to produce a first electrical impulse, means for transferring the stored voltage at the second location to the first location while substantially doubling the voltage, and means for discharging the transferred doubled voltage at the first location to produce a second electrical impulse.

13. Apparatus as claimed in claim 11 and in which there is further provided first means for triggering a gaseous medium to enable the first-named discharging means to discharge through the medium to produce a first light flash, and second means for triggering the medium at a time when the said voltage boosting has been effected to enable the second-named discharging means to discharge through the medium to produce a second light flash.

14. Apparatus as claimed in claim 1 and in which the said rendering means comprises a trigger circuit for producing successive sets of pairs of trigger pulses for producing the said first and second impulse energizations of the load.

15. Apparatus as claimed in claim 14 and in which the time between successive sets of pairs of trigger pulses is greater than the time for storing the said voltages in the first and second energy-storage means.

16. Apparatus as claimed in claim 1 and in which the said voltage-boosting circuit comprises a delay device.

17. Apparatus as claimed in claim 16 and in which the delay device comprises a saturable inductor that resonates with the first and second energy-storage means to effect voltage boosting.

18. Apparatus as claimed in claim 1 and in which means is provided in the said first energy-storing means for preventing overcharging beyond the said predetermined voltage.

19. Apparatus as claimed in claim 18 and in which the said first energy-storing means comprises a charging impedance and the said preventing means comprises a diode shunting the impedance.

20. Electric-impulse-producing apparatus having, in combination, energy-storage means of predetermined

value having high- and low-voltage terminals, a normally ineffective impulse-producing load connected across said terminals, high- and low-voltage energy sources, networks respectively connecting the high- and low-voltage energy sources across the said terminals to store energy in the energy-storage means with a predetermined voltage that, under circumstances of variations of the low voltage energy source, may be exceeded at the high-voltage terminal during the said storing, and clamping means connecting the said high-voltage energy source and the said high-voltage terminal and biased at the said predetermined

voltage for preventing over-storage of the energy-storage means beyond the said predetermined voltage at the said high-voltage terminals, and means for rendering the impulse-producing load effective to discharge the said predetermined voltage stored in the energy storage means.
